MOTOR VEHICLE TRANSMISSION CONTROL LEVER AND MOUNTING THEREFOR

Charles B. McGrew, Jr., Fort Wayne, Ind., assignor to
International Harvester Company, Chicago, Ill., a corporation of New Jersey

Application November 18, 1957, Serial No. 48,514

Term of patent 7 years

(Cl. D14—6)

Figure 1 is a perspective view of my new design;
Figure 2 is a front elevational view; and
Figure 3 is a side elevational view.

A rear elevational view is not shown but it is to be understood the rear of the design is substantially plain.

I claim:

The ornamental design for a motor vehicle transmission control lever and mounting therefor, substantially as shown and described.
